UNITED STATES PATENT OFFICE.

EDOUARD HENRI FREDERIC DE TURCKHEIM, OF PARIS, FRANCE.

DESIGN FOR A MOTOR-CAR BONNET.

45,329.

Specification for Design.

Patented Mar. 3, 1914.

Application filed October 15, 1912. Serial No. 725,913. Term of patent 7 years.

To all whom it may concern:

Be it known that I, EDOUARD HENRI FREDERIC DE TURCKHEIM, a citizen of the French Republic, residing at 4 Rue de l'Arcade, Paris, France, have invented a new, original, and ornamental Design for a Motor-Car Bonnet, of which the following is a specification, reference being had to the accompanying drawings, forming part thereof.

Figure 1 is a perspective view of a bonnet

according to my design. Fig. 2 is an end elevation of the bonnet.

I claim:

The ornamental design for a motor car bonnet as shown.

EDOUARD HENRI FREDERIC DE TURCKHEIM.
